(57) **CLAIM**

The ornamental design for a light bulb, as shown and described.

DESCRIPTION

FIG. 1 is an isometric view of a first embodiment of a light bulb.

FIG. 2 is a front view of the first embodiment of the light bulb of FIG. 1.

FIG. 3 is a back view of the first embodiment of the light bulb of FIG. 1.

FIG. 4 is a left view of the first embodiment of the light bulb of FIG. 1.

FIG. 5 is a top view of the first embodiment of the light bulb of FIG. 1; and,

FIG. 6 is a bottom view of the first embodiment of the light bulb of FIG. 1.

The broken lines in the drawings depict portions of the light bulb that form no part of the claimed design.
